United States Patent Office

Des. 198,084
Patented Apr. 28, 1964

198,084

BANK TELLER'S INPUT/OUTPUT UNIT OR SIMILAR ARTICLE

Robert H. Eytel, North Wales, and Richard S. Massarella,
Philadelphia, Pa., assignors to Sperry Rand Corpora-
tion, New York, N.Y., a corporation of Delaware

Filed July 3, 1963, Ser. No. 75,662

Term of patent 14 years

(Cl. D26—5)

FIG. 1

Des. 198,084

PAGE 2

FIG. 2

FIG. 3

FIG. 1 is a front perspective view of the bank teller's input/output unit or similar article, showing our new design;

FIG. 2 is a rear perspective view; and

FIG. 3 is an elevational view of the right side thereof.

We claim:

The ornamental design for a bank teller's input/output unit or similar article, as shown.
